UNITED STATES PATENT OFFICE

161,875

EXPANSIBLE CHAIN FOR A WATCH BRACELET OR THE LIKE

John F. Sand, Newark, N. J., assignor to Gemex
Company, Union, N. J., a corporation of New
Jersey

Application April 22, 1950, Serial No. 9,432

Term of patent 7 years

(Cl. D45—4)

To all whom it may concern:

Be it known that I, John F. Sand, a citizen of the United States and a resident of Newark, Essex County, State of New Jersey, have invented a new, original, and ornamental Design for Expansible Chain for a Watch Bracelet or the like, of which the following is a specification, reference being had to the accompanying drawing, forming part hereof, in which

Fig. 1 is a top plan view of an expansible chain, embodying my new design;

Fig. 2 is a top plan view thereof illustrating the links in expanded position;

Figs. 3 and 4 are top plan and side elevational views, respectively, of one of the top links of the expansible chain; and,

Fig. 5 is a bottom plan view of the chain.

This application is a continuation-in-part of my application, Serial No. D. 2,719, filed May 18, 1949, which is now abandoned.

I claim:

The ornamental design for an expansible chain for a watch bracelet or the like, substantially as shown.

JOHN F. SAND.
